(57) **CLAIM**

We claim the ornamental design for an air inlet damper, as shown and described.

DESCRIPTION

FIG. 1 is a bottom perspective view of an air inlet damper according to a first embodiment showing the new design in a position of use;

FIG. 2 is a right side view thereof;

FIG. 3 is a left side view thereof;

FIG. 4 is a rear view thereof;

FIG. 5 is a front view thereof;

FIG. 6 is a top view thereof;

FIG. 7 is a bottom view thereof;

FIG. 8 is a bottom perspective view of the air inlet damper of FIG. 1 showing the new design in another position of use;

FIG. 9 is a right side view thereof;

FIG. 10 is a left side view thereof;

FIG. 11 is a rear view thereof;

FIG. 12 is a front view thereof;

FIG. 13 is a top view thereof;

FIG. 14 is a bottom view thereof;

FIG. 15 is a bottom perspective view of an air inlet damper according to a second embodiment showing the new design in a position of use;

FIG. 16 is a right side view thereof;

FIG. 17 is a left side view thereof;

FIG. 18 is a rear view thereof;

FIG. 19 is a front view thereof;
